27 Claims. (Cl. 179—171)

1

This invention relates to amplifiers, and more particularly to electron discharge amplifier devices and circuits associated therewith.

It is a fundamental object of this invention to provide an improved form of electron discharge amplifier device and circuits especially arranged to produce large amplification.

It has often been considered necessary to provide, in an electron discharge amplifier device arranged to produce high gain, a cathode capable of emitting large electron currents. It is, accordingly, a further object of this invention to provide such an improved form of electron discharge amplifier device and circuit in which a cathode capable of emitting only a small space current is provided. When such an electron discharge amplifier device is arranged in accordance with this invention to produce high gain with the cathode emitting only a small space current, simultaneous savings are effected both in the power required to heat the cathode and in the power dissipated in the other elements of the discharge device.

It is a corollary object of this invention to provide such an improved form of electron discharge device and circuit in which only a small number of electrodes is utilized and in which the device and circuit associated therewith is stable in operation and rugged and capable of easy manufacture and assembly.

It is also an object of this invention to provide an improved form of electron discharge device and circuit in which, in a single discharge device, gains in the order of at least 100 are readily obtainable.

The features of this invention which we believe to be novel are set forth with particularity in the appended claims. The invention itself, both as to its organization and manner of operation, together with further objects and advantages thereof may best be understood by reference to the following description taken in connection with the accompanying drawings in which:

Figure 1 is a sectional view in elevation of a preferred form of electron discharge device constructed in accordance with the invention;

Figure 2 is a sectional view of the device illustrated in Figure 1, taken along the line 2—2 in Figure 1;

Figure 3 is a sectional view of an alternative form of the invention, taken as along the line 2—2 of Figure 1;

Figure 4 is a sectional view of a somewhat different form of electron discharge device constructed according to the invention;

Figure 5 is a sectional view of the device illus-

2

trated in Figure 4, taken along the line 5—5 of Figure 4;

Figure 6 is a sectional view of a modified form of electron discharge device similar to that illustrated in sectional elevation in Figure 4;

Figure 7 is still another alternative form of an electron discharge device constructed in accordance with the invention especially for operation at low voltages;

Figure 8 is a sectional view of the device illustrated in Figure 7, taken along the line 8—8 of Figure 7;

Figure 9 is a graph illustrating certain characteristics which may appear in apparatus incorporating the invention;

Figure 10 is a sectional view of still another embodiment of the invention;

Figure 11 is a sectional view of the device shown in Figure 10, taken along the line 11—11 of Figure 10;

Figure 12 is a graph illustrating certain other characteristics which may appear in apparatus incorporating the invention; and

Figures 13 through 18 illustrate circuits especially useful with the various forms of the electron discharge device of the invention.

In Figure 1 an evacuated glass vessel 10 contains a filamentary cathode 11, a first control electrode 12, a first anode 13, a second control electrode 14 and a second anode 15.

The filamentary cathode 11 is fastened at its lower end to a support 16, mounted on a lead-in wire 17 which passes through the wall of the glass vessel 10, and is drawn tense through accurately dimensioned holes in the mica spacers 18 and 19 by a spring 20, to one end of which is fastened the supporting tab 21 on which the other end of the filamentary cathode 11 is fastened. The other end of the spring 20 is fastened to the support post 22 which passes downwardly through the mica spacers 19 and 18 respectively, and to the lower end of which is joined the lead-in conductor 23 which passes through the glass walls of the vessel 10.

A circuit is formed for heating the filamentary cathode 11 from the lead-in conductor 17 through the support 16, the cathode 11, the supporting tab 21, the spring 20, the support post 22, and the lead-in wire 23.

The first control electrode structure is formed by winding a cylindrical conductor of suitable diameter around two supporting posts 24 and 25 helically with the turns of the conductor spaced apart a suitable distance. The supporting posts 24 and 25 are fastened to each turn of the cylind-

drical conductor, as by welding or by providing slots in the posts 24 and 25 within which the cylindrical conductor is wound, the material at each side of the slot being swaged over the cylindrical conductor. The assembled control electrode 12 is placed between the mica separators 18 and 19 with the posts 24 and 25 extending through suitable holes in those separators and the filament 11 is thereafter passed through the holes in the separators 18 and 19 and tensed therein, the holes for the supporting posts 24 and 25 and the holes for the filament 11 being suitably spaced so that accurately determined distances are maintained between the filament 11 and the control electrode 12.

The first anode 13 and the second control electrode 14 are similarly constructed by the winding of a cylindrical conductor around two supporting posts, the diameter of the conductor and the spacing between adjacent turns on the supporting posts being in each case suitable to provide a desired result, as will be explained more fully hereinafter. In each case the supporting posts of the first anode 13 and control electrode 12 and electrode 14 are received within suitably positioned holes in the mica separators 18 and 19 so that accurate spacing is maintained between the control electrode 12, the first anode 13 and the second control electrode 14. It is notable here that, with this construction and arrangement of a discharge device and with circuits to be described hereinafter, it is not necessary to maintain any particular alignment between the turns of the cylindrical conductor of the first control electrode 12, the first anode 13, and the second control electrode 14. In other words, the vertical alignment of the meshes of those three electrodes may be left entirely to chance.

Outside of the second control electrode 14 the anode 15 is arranged cylindrically between the mica spacers 18 and 19 with the axis of the cylinder coincident with the filament 11. The anode 15 is supported by and electrically connected to its supporting post 30, which is placed symmetrically with the supporting post 22, and the upper end of which supports a getter assembly 31. The lower end of the supporting post 30 is connected with a lead-in conductor 32 which extends through the glass wall of the envelope 10 and provides for external electrical connection to the anode 15. Similar lead-in conductors 33 and 34 extend through the glass wall of the envelope 10 and are connected respectively with supporting posts for the first anode 13 and the second control electrode 14, thereby providing external electrical connection respectively with those electrodes. A fixed lead-in conductor 35 passes through the glass wall of the envelope 10 between the lead-in conductor 17 and the lead-in conductor 23, and is connected with the supporting post 25 to provide an external electrical connection for the first control electrode 12.

In Fig. 2, the same numerals are applied to like parts of the discharge device. The central hole through the mica spacer 18 can be seen as a triangle with the filament 11 at one apex. The flat sided first control electrode 12 at its intermediate portions lies relatively close to the filament 11 and the flat sides of the first anode 13 lie a substantially larger distance from the filament 11, the structure of those two electrodes being such that the first control electrode 12 has a relatively large static amplification factor which may be 10 or more.

The second control electrode 14 also has flat

sides substantially parallel with the flat sides of the first control electrode 12 and the first anode 13, and the flat sides of the second control electrode 14 lie substantially closer to the first anode 13 than to the parts of the second anode 15 which receive the electron stream from the cathode 11. That is, the shadowing effect of the supporting posts 24 and 25 is such that the space discharge from the cathode 11 passes substantially perpendicularly through the flat sides of the control electrodes 12 and 14 and first anode 13 to impinge upon only a portion of the anode 15 faced by the flat sides of the inner electrodes.

Purely by way of example, a typical set of dimensions for such an electron discharge device is given to illustrate a specific manner in which the invention may be utilized. The filament 11 is made of tungsten wire a little more than $\frac{1}{16}$ inch in length and of such diameter that 50 milliamperes of current flowing through it produce a voltage drop across it of about $\frac{3}{4}$ of a volt. The helical wire with which the electrodes 12, 13 and 14 are formed is .002 of an inch in diameter. The first control electrode 12 is wound on the supporting posts 24 and 25 with 72 turns per inch, and is so wound that its flat sides are spaced apart by .018 of an inch. That is, the smallest distance between the filament 11 and the control electrode 12 is a little less than .009 of an inch.

The first anode 13 is wound with 50 turns per inch and its flat sides are spaced apart .112 of an inch. The second control electrode 14 is wound with 72 turns per inch and its flat sides are spaced apart .200 of an inch. The diameter of the cylindrical anode 15 is .375 of an inch, and the overall length of all of the elements between the mica spacers 18 and 19 is about $\frac{1}{16}$ of an inch.

Such dimensions provide that the distance between the second control electrode 14 and the first anode 13 is much less than the distance between the second control electrode 14 and effective parts of the anode 15. This spacing between the electrodes, and the close mesh of the second control electrode 14, which is wound with 72 turns per inch, provide that the second control electrode 14 has a relatively high static amplification factor with respect to the anode 15, and that factor may be made in the order of 10 or more.

Such an electron discharge device made in accordance with the invention, the usual precaution being taken as to purity of materials and freedom from contamination within the envelope 10 and with care in evacuating and gettering the device, may be used in circuits as described hereinafter to produce great amplification, as great as several hundred times, while remaining stable in operation. At the same time, the discharge device is simple in construction and rugged and is easy to manufacture.

In general, the construction of the second control electrode 14 is critical, the construction of the remainder of the discharge device being quite similar to that of a normal pentode. The second control electrode 14 may in a preferred form of the invention be placed about twice as far from the anode 15 as from the first anode 13 and may have openings therethrough of such area that, when the second control electrode is substantially at the potential of the cathode 11, space current passing through that second control electrode 14 is affected by the electrode 14 in such a way that, when the potentials on the anodes 15 and 13 are substantially equal, the ratio between current flowing in the first anode 13 and current flowing in the second anode 15 is substantially larger than

the minimum ratio between those currents which is attained when the potential of the second anode 15 is increased indefinitely in a positive direction. This relation may be explained somewhat more simply if a discharge device as illustrated in Figs. 1 and 2 be constructed and substantially equal positive potentials be applied to the anodes 13 and 15, the first control electrode 12 being made slightly negative with respect to the cathode 11 to prevent the flow of unduly large space current from the cathode. With the second control electrode 14 connected to the cathode 11, the current of the first anode 13 is observed and the current in the second anode 15 is observed and the ratio between those two currents is calculated. Then the potential of the second anode 15 is increased positively and consequently the current flowing in the second anode 15 increases asymptotically toward a maximum. At the same time current flowing in the anode 13 decreases asymptotically toward a minimum, and the ratio between the current in the anode 13 and the current in the anode 15 accordingly decreases toward a minimum. The fact that the ratio decreases substantially upon increase in the positive potential of anode 15 is evidence that the discharge device is properly constructed.

This condition does not occur in a normal pentode in which a third electrode is of relatively open mesh, the mesh being so wide that, with the third electrode connected to the cathode, the third electrode produces substantially no effect upon discharge current flowing from the second electrode to the anode. In other words, in a normal pentode, increase of anode potential, as is very well known, does not substantially increase anode current. Expressed in another way, it is frequently said that the internal anode resistance of a normal pentode is extremely high, approaching infinity.

The construction of the second control electrode according to the invention may be described in still another way. The spacing between the first and second anodes and the fineness of mesh are such that, when the second control electrode is operated at cathode potential, or more accurately at a potential near that potential at which electron current begins to flow into the second control electrode, and when there are substantially equal positive potentials on the anodes, current flowing in the second anode 15 is substantially less than the current which would flow in the second anode 15 with substantially equal positive anode potentials but with a more positive potential on the second control electrode 14. This may be clearer if the steps in testing the construction are explained in detail. Normal positive potentials are applied to the anodes 13 and 15, and a slight negative potential is applied to the first control electrode 12, just sufficient to cause normal space current to flow from the cathode 11. The potential of the control electrode 14 is adjusted in the region of cathode potential so that electron current just begins to flow in the second control electrode 14. The current flowing into the second anode 15 is then observed and the potential of the second control electrode 14 is changed in a positive direction, and the current flowing in the anode 15 increases, which indicates that the control electrode 14 is correctly constructed. The current in the second anode should increase at least 25%, and it is actually preferred that the second control electrode be so constructed that the current in the second anode substantially doubles when the second control electrode poten-

tial is increased under the described conditions. That is, the current in the second anode to begin with should be at least one-fifth less than the current which flows in the second anode after the second control electrode potential is made substantially more positive, and it is preferred that the second anode current be in the order of half the current which flows in the second anode after the second control electrode potential is made more positive. It is another aspect of this peculiar construction of the second control electrode that it is capable of effecting substantial changes in electron current distribution between the two anodes when its potential is changed in small increments, its average potential being near cathode potential. That is, the static amplification factor of the second control electrode is sufficiently high that, when it is near cathode potential, it has a substantial influence on the distribution of space current between the first and second anodes.

There is still another test which may be used for certain types of discharge device constructed according to this invention. With the preferred form of second control electrode, when the potentials on the first control electrode 12 and first anode 13 are adjusted so that substantial space current flows to the first anode 13, and with the second control electrode 14 near cathode potential, or more accurately near that potential at which current begins to flow in the second control electrode 14, space current does not flow to the second anode as its potential rises from zero voltage with respect to the cathode to a substantially positive voltage when the second control electrode 14 is correctly constructed. The second anode 15 may even rise to a positive voltage with respect to the cathode which is ten or twenty per cent. or even more of the positive voltage on the first anode 13 without any measurable current flowing in the second anode 15.

As a general rule, the structures at the first and second control electrodes will be somewhat similar insofar as their mesh and the size of the conductor from which they are wound is concerned.

It should be noted at this point that, while it is preferred to have the second control electrode 14 closer to the first anode 13 than to the second anode 15, the second control electrode 14 can be constructed to produce the requisite results without being so spaced. In this connection, it should be pointed out that the term "closer" must be differently interpreted when applied to different forms of control electrode. Where the control electrode 14 is flat sided as illustrated in Fig. 2, the term "closer" should be given the natural meaning that the actual distance between the first anode 13 and the control electrode 14 is less than the actual distance from the control electrode 14 to the anode 15, always remembering, of course, that these distances should be measured along a line perpendicular to the filamentary cathode 11 and perpendicular to the flat sides of the electrodes 13 and 14.

Where the electrode 14 is made generally cylindrical, the term "closer" must be given the meaning that the ratio of the diameter of the first anode 13 to the diameter of the second control electrode 14 is greater than the ratio of the diameter of the second control electrode 14 to the anode 15.

In Fig. 3, there is illustrated a cross section of a discharge device which appears in sectional elevation like the device illustrated in Fig. 1, the section shown in Fig. 3 being taken as along the line

2—2 of Fig. 1. In the device of Fig. 3, parts similar to those illustrated in Figs. 1 and 2 are given like reference numerals. A somewhat different second control electrode 40 is arranged between the first anode 13 and the second anode 15. This second control electrode 40 is roughly cylindrical. The second control electrode 40 is made of such diameter that it is closer to the second anode 15 than to the first anode 13. While this is not generally a preferred construction of the invention, it is possible to construct a device in this manner and achieve results falling within the scope of the invention. Purely by way of example, certain dimensions of the device illustrated in Fig. 3 are given to illustrate how the second control electrode 40 can be made so that it has a sufficiently large static amplification factor to achieve the desired result. The filament 11, the over-all length between the mica spacers 18 and 19 of the elements, and the size and spacing of the supporting posts may all be like those shown and described in connection with Fig. 1. Also, the spacing between the flat sides of the first control electrode 12 may be .018 of an inch and the spacing between the flat sides of the first anode 13 may be .112 of an inch. However, the spacing between the sides of the second control electrode 40 along a line perpendicular to the filament 11 and perpendicular to the flat sides of the first anode 13 is made .250 of an inch, and along that same line the diameter of the anode 15 is made .320 of an inch.

Such an arrangement as illustrated in Fig. 3 has in the second control electrode 40 a smaller static amplification factor than if the electrode 40 were closer to the first anode 13 than to the second anode 15, but the second control electrode 40, having 72 turns per inch of cylindrical conductor .002 of an inch in diameter, is, when near cathode potential, capable of substantially influencing the current distribution between the anodes 13 and 15.

In Fig. 4, there is illustrated an electron discharge device which is especially constructed for operation at substantially lower electrode potentials than the device illustrated in Fig. 1. Many elements are similar to the elements illustrated in the device of Fig. 1 and are given like reference characters. The first control electrode 50, the first anode 51, second control electrode 52, and the second anode 53 are all constructed with different dimensions from the corresponding electrodes of Fig. 1 for the purpose of providing lower potential operation. The first control electrode 50 is made of somewhat more open mesh so that a relatively low positive potential on the first anode 51 is effective to draw a substantial electron current flow from the cathode 11 through the first control electrode 50. Similarly, the second control electrode 52 is made with somewhat more open mesh so that the anode 53 can draw a substantial electron current flow through the control electrode 52 from a space charge formed between the control electrode 52 and the first anode 51.

By way of example, to illustrate one manner in which the device of Fig. 4 may be constructed, the first control electrode 50 may be wound with 64 turns per inch of cylindrical conductor .002 of an inch in diameter, wound helically around the supporting posts 24 and 25. The first anode 51 may be wound with the same size conductor, but with 50 turns per inch, and the second control electrode 52 may be wound with the same size conductor but with 64 turns per inch.

In Fig. 5, like parts are given the same reference numerals and the shapes of the electrodes 50, 51, 52 and 53 may be seen somewhat more clearly. The control electrodes 50 and 52 and the first anode 51 are wound with flat sides, like the corresponding electrodes shown in Fig. 2, and the anode 53 is cylindrical. The spacing between the opposite flat sides of the first control electrode 50 is .018 of an inch, and the spacing between the opposite flat sides of the first anode 51 and the second control electrode 52 are respectively .086 of an inch and .136 of an inch. The diameter of the anode 53 is .250 of an inch.

With the second control electrode 52 substantially closer to the first anode 51 than to the second anode 53, and with the first anode 51 relatively closer to the first control electrode 50, the two control electrodes being of more open mesh, the anodes 51 and 53 may be operated at lower potentials than is the case with the device illustrated in Fig. 1. For example, anode supply potential for the device of Figs. 4 and 5 may be in the order of 20 to 30 volts. Even with such open mesh in the control electrodes, it is desirable that the static amplification factor of each control electrode with respect to its associated anode be at least in the order of 10 in order to achieve the new results of the invention.

It is important to note that anode potentials cannot be made indefinitely low. Contact potentials, which are in the order of one volt, and which are due to surface conditions of the various electrodes, the surface conditions being frequently altered by contamination with cathode coating material, may affect very undesirably the anode currents. Such contact potentials vary markedly from one discharge device to another and furthermore they vary during use of the discharge device. These contact potentials affect the actual potential of every electrode in the discharge device, and particularly affect the effective bias potential of the second control electrode. If the static amplification factor of the second control electrode is high, the supply potential for both anodes must be high compared to the contact potential of the second control electrode multiplied by its static amplification factor. If the supply potential for the anodes is not high compared to the contact potential of the second control electrode times its static amplification factor, the contact potential may affect the anode current adversely, and might even cut off completely the current flowing in the second anode. In any case, in the particular circuits with which this discharge device is particularly adapted to be used, it is undesirable that the contact potential of the second control electrodes affect the current in either anode to any large extent.

Bearing in mind the effect of contact potential of the second control electrode, where those contact potentials are in the order of one volt (as they usually are), it is evident that, if it be desired to operate the anodes from supply potentials in the order of twenty volts, the static amplification factor of the second control electrode should not exceed a factor in the order of 10. Anode supply potentials lower than about 15 volts cannot safely be used, unless contact potential is reduced correspondingly lower than 1 volt.

In Fig. 6, there is illustrated in cross section taken perpendicular to the filamentary cathode a discharge device similar to that illustrated in Figs. 1 and 2, but with a modified second anode.

Like reference numerals are applied to similar parts. Different mica spacers are provided, of which the lower one 60 is illustrated, in order to support the filamentary cathode 11 and the first control electrode 12, first anode 13, and second anode 14 off center with respect to the glass envelope 10. An anode 61, of relatively small area compared to one of the flat sides of the second control electrode 14, is supported on a supporting post 62 between the mica separators and is placed substantially symmetrically with respect to a plane passing through the filament 11 perpendicularly to the flat side of the second control electrode 14.

By way of illustration, the dimensions for a device made in accordance with Fig. 6 may be as follows. The spacings between the flat sides of the control electrode 12 are the same, being .018 of an inch, and similarly the spacings between the flat sides of the first anode 13 and of the second control electrode 14 are the same, being respectively .112 of an inch and .200 of an inch. The distance from the filamentary cathode 11 to the small anode 61 is .187 of an inch. As is the case with the device illustrated in Fig. 1, the mesh of the electrodes 12, 13 and 14 is respectively 72 turns per inch, 50 turns per inch, and 72 turns per inch.

By making the area of the anode 61 small, and in fact substantially smaller than the effective area of the second control electrode 14, the internal anode resistance of the anode 61 is made high and the effect of potential changes on the second control electrode 14 upon the flow of current to the first anode 13 is substantially reduced. This structure of an electron discharge device is especially useful in a special circuit employing regeneration. That is, in a circuit in which potential changes appearing on the first anode 13 (when signal potentials are impressed on the first control electrode 12) are impressed upon the second control electrode 14, the discharge device acts not only like a cascaded pair of triode amplifiers, but also acts regeneratively. The regenerative effect, of potentials impressed on second control electrode 14 by the first anode 13, upon the space current flowing to the first anode 13 may be so great as to cause self-induced oscillation. By making the area of the anode 61 small, the effect of the second control electrode 14 upon current flowing to the first anode 13 is reduced, so that the regenerative effect can be made high enough to give useful results but not so high that self-induced oscillations are produced.

Expressed in other words, the control electrode 14 is normally used, as explained previously, to cause a change in the current distribution between the first anode 13 and the second anode 61. When potential changes appearing on the first anode 13 are impressed on the second control electrode 14, the change in current distribution between the anodes 13 and 61 caused by the resulting effect of the second control electrode 14 is in aiding relation on the first anode 13 and is therefore regenerative. This is true because an increase in the total cathode current from the filament 11, caused by a change in potential in the first control electrode 12, causes a reduction in the positive potential of the first anode 13 and, when such reduction in potential is impressed on the second control electrode 14, causes a still further reduction in the potential of the first anode 13 by reason of the still further increased current flowing into the anode 13 because of 75

the change in current distribution between the anodes 13 and 61 induced by the change in potential on control electrode 14. This change in current distribution between the anodes 13 and 61 is sufficient to cause the potential of anode 61 to rise instead of fall as it would if the potential of second control electrode 14 had not changed. Because the anode 61 is small, the first anode 13 takes substantially all of the electron current from the cathode 11 over most of its area and the control electrode 14 is therefore not effective to change the anode current distribution between anodes 13 and 61 as much as if the anode 61 entirely surrounded the control electrode 14. Consequently, the regenerative effect of potential changes of second control electrode 14 upon the first anode 13 may be made sufficiently small that self-induced oscillations cannot be started. Stable operation is therefore possible.

20 In Figure 7 there is illustrated an alternative form of electron discharge device which is especially suitable for operation with low anode supply potential, and without any sacrifice in gain by increase in mesh size of control electrode as 25 in the case of the device illustrated in Figures 4 and 5. In this figure many elements are similar to those illustrated in Figure 1 and are given like reference character. A space charge electrode 70 is provided adjacent to the filamentary cathode 11, and is followed consecutively by a first control electrode 71, a first anode 72, a second control electrode 73, and a second anode 74. These electrodes are all held in proper spaced relation by suitable mica spacers 75 and 76. The space 30 charge electrode 70 is provided with an external connection through a lead-in conductor 79 extending through the glass wall of the envelope 10.

The space charge electrode 70 is constructed so that it may be operated at a small positive potential, with the result that a substantial cathode current is caused to flow through the first control electrode 71 to the first anode 72, even though the first anode 72 is operated with a very small anode supply potential (for example, as low as 45 fifteen volts) and even though the static amplification factor of the first control electrode 71 with respect to the first anode 72 is substantial. In such a device, as in the ones previously described, the static amplification factor of the second control electrode 73 may be made high with respect to the anode 74, even though the anode supply potential for the anode 74 is very low, for example, as low as fifteen volts.

By space charge electrode in the present specification and claims it is understood that reference is made to an electrode of potential positive with respect to the cathode and immediately adjacent thereto without the presence of other electrodes theretwixen.

60 As a specific example, to illustrate exactly how one device of the type illustrated in Fig. 7 may be constructed, the space charge electrode 70 may be wound with 64 turns per inch of cylindrical wire of two thousandths inch diameter, the first control electrode 71 with 80 turns per inch, the first anode 72 with 50 turns per inch, and the second control electrode 73 with 72 turns per inch, all being wound with cylindrical wire of two thousandths of an inch diameter.

70 In Fig. 8, being a sectional view along the line 8-8 of Fig. 7, it is evident that the first control electrode 71 is closer to the cathode 11 and to the space charge electrode 70 than it is to the first anode 72, and similarly the second control electrode 73 is closer to the first anode 72 than it

is to the second anode 74. As a specific example, the diameter of the electrode shown in Fig. 8, wound like those described specifically in connection with Fig. 7, such diameters being taken along a line perpendicular to the filamentary cathode 11 and to the flat side of the second control electrode 73, may be respectively 0.018 inch, 0.047 inch, 0.125 inch, 0.2 inch, and 0.375 inch.

Such an arrangement as shown in Figs. 7 and 8, in which a space charge electrode 70 is provided is especially useful in connection with apparatus such as a hearing aid in which it is highly desirable, not only that low potential be necessary for all of the electrodes, in order that very small wearable batteries may be utilized to supply the potentials, but also that the current and power drain required by the discharge device be extremely small, so that the small wearable batteries may have reasonably long life.

In Fig. 9 certain operating characteristics of all the discharge devices so far described are illustrated, anode currents being plotted as ordinates, against second anode voltages, as abscissae. The characteristics illustrated are present in these discharge devices, provided cathode temperature is high enough that electron emission from the cathode is not temperature limited. When the second anode voltage is very low, and with a fixed first anode potential high enough to cause a substantial first anode current to flow with a zero potential on the second anode, with a small negative bias potential with respect to the cathode on the first control electrode, and with the second control electrode maintained at cathode potential, or more accurately at that potential at which the second control electrode just begins to take electron current, all current flows to the first anode. Curve 80 illustrates the variation in first anode current under those conditions as the second anode voltage is increased from zero volts with respect to the cathode to a high positive voltage, and curve 81 illustrates the variation in the current flowing in the second anode as the second anode voltage is so changed.

Curve 80 shows that the first anode current is of substantial amount when the second anode voltage is zero with respect to the cathode and remains substantially constant as the second anode voltage is increased to a substantial positive voltage with respect to the cathode. At some substantial positive second anode voltage, for example, a voltage in the order of ten volts, the first anode current begins to decrease as the second anode voltage increases, and continues decreasing, finally approaching a limiting minimum current which does not decrease as the second anode voltage approaches infinity.

Curve 81 illustrates that the second anode current is zero when the second anode voltage is zero with respect to the cathode, and remains zero as the second anode voltage is increased in a positive direction to a substantial positive voltage, for example, in the order of ten volts. As the second anode voltage increases further in a positive direction, the second anode begins to take current from the first anode (the total of the first anode current and the second anode current increasing gradually), and the second anode current increases through the range where the first anode current decreases, finally approaching asymptotically a maximum current as the second anode voltage increases toward infinity.

There is a particular second anode voltage at which the curves 80 and 81 cross, and at which the first anode current and the second anode

current are substantially equal. It is between that second anode voltage at which the anode currents are equal and that second anode voltage at which the second anode current first appears that it is preferred to operate the discharge device made according to this invention. With the second control electrode constructed in accordance with the invention, the anode currents and the anode voltages within this preferred operating range are of normal and reasonable magnitude, and the discharge device may be used with various circuits to produce extremely high gain amplification. With the second control electrode so constructed according to the invention, the second anode voltage is impractically high, and too high for practical operation of the discharge device, where the second anode current is near maximum and the first anode current near minimum. It is in that region that the normal pentode operates, and it is able to operate in that region with a smaller anode voltage by reason of a different construction of its third grid, commonly called the suppressor. The suppressor electrode in a normal pentode is made with an open mesh so that it does not substantially affect the current distribution between the screen electrode and the anode while the suppressor is near cathode potential.

In Figure 10 an evacuated glass vessel 90 contains 5 electrodes constructed according to the invention, of which the cathode 91 is indirectly heated. With the indirectly heated unipotential cathode 91 more space current is caused to flow to the anodes 92 and 94, and those anodes are arranged for operation at higher positive potentials with respect to cathode 91 than is the case with the devices illustrated in Figures 1 through 8, that is, the discharge device illustrated in Figure 10 is constructed so that the anode supply potential for the anodes 92 and 94 may be in the order of 200 volts, and should be in the order of at least 45 volts. The first control electrode 93, between the first anode 92 and the cathode 91, and the second control electrode 95 between the first anode 92 and the second anode 94, are both made to have a relatively high static amplification factor. The second control electrode 95 may, for example, be so constructed that its static amplification factor is in the order of 25 or more, thereby necessitating that the supply potential for the second anode 94 be large relative to the static amplification factor of the control electrode 95 multiplied by the contact potential, which is in the order of 1 volt.

Except for the construction of the five electrodes of the discharge device in Figure 10 so that the anodes operate at higher positive potentials, and so that the control electrode 95 has a higher static amplification factor, the general principles of the construction and operation of this discharge device are much the same as those illustrated in Figures 1 through 8.

Purely by way of example, specific dimensions for the electrodes are given. The diameter of the cylindrical unipotential indirectly heated cathode 91 is 0.047 inch. The first control electrode 93 is formed of wire 0.003 inch in diameter, wound spirally around two supporting posts 96 and 97 with 52 turns per inch. The first anode 92 is formed of wire whose diameter is 0.003 inch wound spirally around two supporting posts 98 and 99 with 40 turns per inch. The second control electrode 95 is formed of wire whose diameter is 0.002 inch wound spirally around two supporting posts 100 and 101 with 72 turns per

inch. The second anode 94 is formed of sheet metal having flat wing portions on opposite sides of the heated cathode 91.

In Figure 11 a sectional view of the device shown in Figure 10 taken along the line 11—11 illustrates more clearly the general shape of the various electrodes of the device in a plane perpendicular to the axis of the cathode 91. The wings 102 and 103 of the anode 94 lie parallel to each other and are spaced apart 0.600 inch. The wings 102 and 103 lie in planes which are parallel with the axis of the indirectly heated cathode 91. The second control electrode 95 has flat sides which are generally parallel with the wings 102 and 103 of the anode 94, and the flat sides of the second control electrode 95 are spaced apart by 0.270 inch. Similarly, the first anode 92 has flat opposite sides generally parallel with the wings 102 and 103 of the anode 94, and the flat opposite sides are spaced apart by 0.172 inch. The distances by which these flat sides are spaced apart are all measured along a line perpendicular to the axis of the cathode 91 and to the planes 102 and 103 of the anode 94. Along that same line the opposite curved sides of the first control electrode 93 are spaced apart by 0.075 inch. It should be noted that the opposite sides of the first control electrode 93 are not flattened, but are rounded, so that the control electrode 93 is substantially equidistant from all emitting parts of the cathode 91. The shadowing effect of the control electrode supporting posts 96 and 97 is effective to suppress electron emission from portions of the surface of the cathode 91 near a plane passing through the supporting posts 96 and 97.

The electrodes 91 through 95 are all supported in symmetrical relation with each other between mica spacers 104 and 105, which in turn are held in proper relation to one another and to the glass vessel 90 by metal caps 106 and 107 which are held apart in fixed relation by posts 108 and 109. A suitable getter assembly 110 is supported in any desired fashion in the upper portion of the envelope 90.

Individual external connections for the five electrodes 91 through 95 are provided, each extending through the glass wall of the envelope 90. A lead-in conductor 111 provides an external connection for the unipotential cathode 91. A lead-in conductor 112 provides an external connection for the first control electrode 93. Lead-in connections 113, 114 and 115 respectively, provide external connections for the first anode 92, second control electrode 95, and second anode 94. Lead-in conductors 116 provide external connections through which suitable continuous or alternating current may be supplied to a resistance heater within the unipotential cathode 91.

In Figure 12 certain characteristics of a discharge device constructed in accordance with this invention are presented in a somewhat different light than in Figure 9. In Figure 12 the currents flowing in the second anode are plotted as ordinates and the potentials of the second anode are plotted as abscissae. Curve 120 is similar in significance to curve 81 of Figure 9 being taken with a fixed positive potential on the first anode, with a small negative bias potential on the first control electrode, and with no bias potential on the second control electrode. That is, curve 120 is taken with the second control electrode connected to the cathode, or more

accurately, adjusted to that potential at which current just begins to flow in it.

Curve 121 may be observed under similar conditions, but with the potential of the second control electrode made a little more negative than is the case with curve 120. The curves illustrate that the second anode current is throughout the operating range, with a substantial negative bias potential on the second control electrode substantially less than with no bias potential on the second control electrode.

By referring to points on the curves 120 and 121 on a perpendicular line, such as the line 122, it may be determined how much current change 15 can be expected in the second anode (delta I) in response to a predetermined small voltage change of the second control electrode, the first and second anode voltages remaining constant. Of course, in actual use, application of a small negative bias potential to the second control electrode tends to decrease the second anode current with a corresponding increase in the second anode voltage, because the second anode must be connected to a source of supply potential through 20 a load impedance. Consequently, when a load impedance is connected with the second anode, the actual change, or reduction, in said second anode current upon an increase in negative bias potential of the second control electrode is 25 smaller than might otherwise be expected. Expressed another way, the static transconductance from the second control electrode to the second anode is always greater than the transconductance between those two electrodes measured 30 with a load impedance connected with the second anode.

As pointed out previously, the peculiar construction of the second control electrode makes it possible to have these control characteristics with 35 the second control electrode in the region of cathode potential. The normal pentode with a suppressor electrode operates at second anode voltages above the operating range indicated in Figure 12, and a suppressor electrode has a negligible transconductance over a substantial range of voltage near a cathode voltage. As a matter of fact, the second anode current does not drop to zero until the second anode voltage has reached zero voltage with respect to the cathode, unlike 40 the characteristic of the preferred form of discharge device according to the invention in which the construction of the second control electrode keeps the second anode current at zero even while the second anode voltage is at substantial 45 positive level.

In Figure 13 the discharge device 130, constructed in accordance with this invention, is connected with a special circuit and provides very high gain amplification in that circuit. For 50 convenience in understanding the construction and operation of the discharge device 130, it will be assumed that it is identical with the discharge device described in Figures 1 and 2, and the same reference characters will be used for parts of the 55 discharge device. It should be understood, of course, that any other discharge device constructed in accordance with the invention, and particularly any of the devices illustrated in Figures 1 through 8 or in Figures 10 and 11 might be utilized as the discharge device 130, if suitable 60 electrode supply potentials are provided.

One terminal of the filament 11 is grounded and a suitable source 131 of filament heating current is connected between the two terminals of 65 the filament 11. When a filamentary source 11

as illustrated in Figure 1 is utilized, the source 131 should provide continuous current for heating the filament 11, as from a primary or secondary battery or a source of rectified alternating current. If, however, the filament 11 be replaced by an indirectly heated cathode, the heating current from the source 131 may be either alternating or continuous current. A source 132 of signal potential is connected between the first control grid 12 and the grounded terminal of the cathode 11. The negative terminal of a source 133 of anode current is connected to one terminal of the filament 11, and the positive terminal of the source 133 is connected through a resistance 134 to the first anode 13. A resistance 135 is connected between the second control electrode 14 and ground and a condenser 136 is connected between the second control electrode 14 and the first anode 13. The second anode 15 is connected through a resistance 137 to the positive terminal of the source 133.

Small potential variations impressed from source 132 between the first control electrode 12 and the cathode 11 appear as amplified potential variations upon the first anode 13, and such amplified potential variations across the resistance 134 are impressed through the coupling condenser 136 to resistance 135. Potential variations across the resistance 135 appear on the second control electrode 14, wherefor current distribution between the anodes 13 and 15 is adjusted in accordance with such potential variations. As explained previously, the effect of this adjustment of current distribution between the anodes 13 and 15 by amplified potential variation from the anode 13 impressed upon the second control electrode 14, is regenerative in nature and therefore increases the magnitude of the amplified potential variation on the anode 13.

The greatly amplified potential variations thus appearing on the second control electrode 14 appear in still greater amplified intensity on the second anode 15 and across the resistance 137. The potential variations across the resistance 137 are coupled by a coupling condenser 138 to any desired load 139. Hereafter, when reference is made to resistance 137, it should be understood to mean the entire load impedance associated with anode 15, including load 139, stray capacities, etc.

To understand clearly the operation of the circuit illustrated in Figure 13, it should be borne in mind that the potential variations appearing on the anodes 13 and 15 are opposite in phase. If it be assumed at a particular instance of time that the positive potential of the first anode 13 is decreasing it causes a corresponding change in the potential of the second control electrode 14 in the negative direction. This potential change on the second control electrode 14 at once does two things. It simultaneously causes a decrease in the current flowing in the second anode 15, with a consequent increase in the potential of the anode 15 in the positive direction, and also causes an increase in the current flowing in the first anode 13, with a corresponding even greater decrease in the potential of the anode 13. It is evident therefore that a decrease in the potential of the anode 13 causes a corresponding change in the potential of the second control electrode 14 in a negative direction, which in turn causes again a decrease in the potential of the anode 13, which action is regenerative.

In order that the over-all gain of the discharge device 130 in the circuit illustrated be as high as possible, consistent with stable operation, the re-

generation between the second control electrode 14 and the first anode 13 should be made as great as possible without causing self-induced oscillation.

For proper operation of this device, the reactance of the condenser 136 should be sufficiently small with respect to the magnitude of the resistances 134 and 135 that substantially all of the potential variation appearing on the first anode 13 is transferred to the second control electrode 14. As a general rule, the resistances 134, 135 and 137 should be large compared with the internal resistance of the anodes 13 and 15. Now, if the relative magnitude of those resistances 134, 135, and 137 is made such that the maximum possible gain of the discharge device 130 is achieved by using the maximum amount of regeneration between the control electrode 14 and the anode 13 without producing oscillation within a desired frequency range, the regeneration will be found to change with frequency in such a manner that oscillation is possible at some frequency outside that desired range.

Consequently, with the form of circuit shown in Figure 13, the resistance 134 must be made substantially smaller than the resistance necessary to achieve maximum gain in the desired range of frequencies, to avoid oscillation at a frequency outside that range, with the result that a smaller gain must be accepted in the desired range. This condition of freedom from oscillation can be achieved in either of two ways. Resistance 137 may be selected to provide a desired frequency response, anode current, output power, etc., and resistance 134 made small enough to prevent oscillation at any frequency. Alternatively, resistance 134 may be made to provide a desired current in first anode 13, or it may be chosen for other reasons, and resistance 137 made large enough to prevent oscillations. Over a wide range of variation, there is required a minimum ratio between resistance 137 and resistance 134.

The whole phenomena can be viewed in another way, in that oscillation occurs because the negative transconductance between the second control electrode 14 and the first anode 13 increases as frequency increases for the reason that the load impedance connected with the anode 15 is not purely resistive but has capacity effectively in shunt with it. This capacity may be in the load 139 or may be simply stray circuit capacity, including inter-electrode capacity, and when very high gains are involved, such capacities can cause oscillation. The dynamic negative transconductance between the second control electrode 14 and the first anode 13 is sufficient to cause oscillation if it is equal to or greater than the sum of the reciprocals of the load impedance connected with the first anode 13 and the internal resistance of the first anode 13. This relation of course assumes that the load impedance connected with the second anode 15 and all supply voltages are constant. Inspection of the relation immediately indicates that a decrease either in the load impedance connected with the anode 13 or in the internal resistance of the anode 13 makes it less likely that oscillation can occur.

In all circuits of the general type illustrated in Figure 13, the resistances 134 and 137 should preferably be of such magnitude that the current flowing in the anode 15 is less than the current flowing in the anode 13. This relation is illustrated in Figure 9 as making the device operate in the preferred operating range. It is at least

necessary that the resistances 134 and 137 be so adjusted that the ratio of current in the anode 15 to current in anode 13 is substantially smaller than the maximum ratio reached when the device is connected as illustrated and the supply potential for the anode 15 is increased indefinitely. This latter relation exists when the device is operated in the indicated operating range of Figure 12.

These conditions may be readily satisfied in a preferred arrangement wherein the current in anode 13 is substantially larger than the current in anode 15, and where the potentials on these anodes are of the same order of magnitude, by supplying current to the anodes from a common source and making the load resistance 137 substantially larger than the load resistance 134.

Another consideration in choice of magnitudes for the resistances 134 and 137 is that, even though the resistance 137 should be larger than the resistance 134, the ratio of magnitude of resistance 137 to resistance 134 should be not more than the static voltage amplification factor of the second control electrode 14 with respect to anode 15.

An exact analysis of the conditions requisite in this circuit for avoidance of oscillations follows. The analysis leads to a choice of load impedances 134, 135 and 137 in the return of the first and second anodes. By the term "load impedances" is meant not only the illustrated resistances, but also circuit capacities (such as stray capacity) and circuit inductances, any of which may be added deliberately. To obtain a formula by which may be selected load impedances within which oscillation cannot occur, it must be borne in mind that the admittance prevailing between the first anode 13 and ground must remain positive and finite over the entire frequency range. This admittance consists of the sum of the internal admittance $1/R_1$ of the first anode 13 (with all other electrodes kept at constant potential), the admittance in the external circuit of the first anode (which admittance is reciprocal to the impedance Z_1) and the effective trans-conductance G_F from the second control electrode 14 to the first anode 13. Z_1 is the external impedance between anode 13 and ground, and includes resistances 134 and 135, stray circuit capacities and other effective circuit capacities and any effective circuit inductances. The trans-conductance G_F is negative in sign, because a more positive potential on the second control electrode 14 causes more current to flow to the second anode 15 so that less current flows to the first anode 13. Potential variations of the second anode 15 affect the current to the first anode 13 in a similar manner, the effect of the second anode 15 being obtained by dividing the potential variations at the second anode 15 by the static amplification factor from second control electrode 14 to second anode 15. The potential variations at the second anode 15 can be derived from those at the second control electrode 14 by using conventional triode computations, and substitution leads to an expression for trans-conductance G_F from the second control electrode 14 to the first anode 13.

$$(1) \quad G_F = G_M \frac{R_2}{R_2 + Z_2}$$

In which G_M is the static trans-conductance from control electrode 14 to the first anode 13, other electrodes being maintained at constant potential (especially anode 15); and in which R_2 and Z_2 are respectively the internal resistance and external load impedance associated with anode 15, analo-

gous to R_1 and Z_1 . The condition of a finite positive sum of admittances can now be written in the following form:

$$5 (2) \quad \frac{1}{R_1} + \frac{1}{Z_1} - G_M \frac{R_2}{R_2 + Z_2} > 0$$

which can be simplified:

$$10 (3) \quad \left(\frac{1}{Z_1} + \frac{1}{R_1} \right) (Z_2 + R_2) > G_M R_2$$

and:

$$15 (4) \quad \frac{(R_1 + Z_1)(R_2 + Z_2)}{R_1 Z_1} > G_M R_2$$

It is evident by inspection of Equations 3 and 4 that oscillations may be suppressed by (a) an increase in the magnitude of load impedance Z_2 (as by increase in resistance or inductance or decrease in capacity), (b) a decrease in G_M by appropriate construction of the device (Fig. 6), (c) a decrease in internal resistance R_2 , other factors remaining constant, (d) a decrease in internal resistance R_1 by appropriate construction of the device, or (e) a decrease in Z_1 as by decrease in its resistance or inductance or an increase in capacity.

In utilizing the above relation in the design of commercial circuits, it should be remembered that 30 the relation should be satisfied within the range of tolerances of commercially available circuit elements. To achieve maximum gain, it is desirable furthermore that the inequality have a minimum within or near the desired range of operating 35 frequencies.

While it is possible to avoid self-induced oscillation in the circuit arrangement of Figure 13 as described, (by making the ratio of resistance 137 to resistance 134 large enough) it is preferred 40 to make such oscillations impossible in a somewhat different manner.

Referring to inequalities (3) and (4), it is preferred to suppress oscillation by adjusting not only the resistive components of the load impedances Z_1 and Z_2 but also the reactive components (usually capacity) so that the inequality 45 (4) is satisfied at all frequencies.

In Figure 14, such an arrangement is illustrated, and since many elements are similar to those illustrated in Figure 13, like reference numerals are applied. A condenser 140 is connected in shunt with the resistance 134 and is of such magnitude that the time constant existing between the first anode 13 and ground is similar in magnitude to the time constant existing between the second anode 15 and ground. Expressed in single terms, the condenser 140 is increased until no oscillation is possible.

The condenser 140 is connected effectively for 60 alternating current between the first anode 13 and ground to achieve this purpose, rather than between the second anode 15 and ground, because, as stated previously, when a common source 133 of anode current is used, the resistance 137 65 must be substantially larger than the resistance 134 and consequently the capacity associated with the second anode 15 must be smaller than that associated with the first anode 13. Since stray circuit capacities and inter-electrode capacities associated with the first anode 13 are normally smaller than those associated with the second anode 15, it is usually necessary to add additional capacity in the form of the condenser 140 in order that the desired relation should be achieved.

75 By the addition of the condenser 140, so that

the time constant of circuits associated with the first anode 13 is similar to the time constant of circuits associated with the second anode 15, the ratio of the absolute magnitude of the impedances associated respectively with the two anodes may be made to satisfy the inequality (4).

The impedance associated with the anode 13 is, by the condenser 140, made to decrease just fast enough in relation to the impedance associated with the anode 15 that this relation is satisfied.

In Fig. 15 there is illustrated a circuit arrangement which is capable of satisfying that expression more accurately. Again, since many circuit elements are similar to those illustrated in Fig. 13, they are given like reference numerals. A serial combination of a condenser 150 and the resistance 151 are connected in shunt with the resistance 134. The capacity of the condenser 150 with the resistance 151 can be given such magnitude as more nearly to satisfy the relation that the product of the sum of the impedance Z_1 associated with anode 13 and the internal resistance R_1 of anode 13 and the sum of the impedance Z_2 associated with anode 15 and the internal resistance R_2 of anode 15 divided by the product of R_1 and Z_1 is always greater than the product of the internal resistance R_2 of anode 15 and the static trans-conductance G_m from the second control electrode 14 to the first anode 13. That is, if there is a purely capacitive impedance connected between the first anode 13 and ground, as the condenser 140 in Fig. 14, the impedance associated with anode 13 approaches zero as frequency increases toward infinity. To satisfy the desired relation, however, the impedance between the anode 13 and ground need not approach zero, but must in any case decrease to a positive limiting magnitude as frequency increases toward infinity. That limiting impedance is substantially the resistances 134, 135 and 151 in shunt with each other. The condenser 150 is of such capacity that, in the operating range of frequencies, the relation is satisfied within the tolerance of available circuit elements whereby the gain of the system is as high as possible.

In Fig. 16 there is illustrated the circuit arrangement which is especially useful with certain types of loads. Where an amplifier circuit arranged according to this invention feeds a load which may under certain circumstances change impedance abruptly by substantial amounts, it is highly desirable to isolate that load from the amplifier. Since, again, many of the elements illustrated in Fig. 16 are similar to those illustrated in Fig. 13, they are given like reference characters.

The load device in Fig. 16 which is coupled to the second anode 15 through the coupling condenser 138 includes an electron discharge amplifier device 160 of the tetrode type which is connected in normal fashion and with its anode 161 coupled with a load 162. The control electrode 163 of the device 160 is connected through a resistance 164 to the coupling condenser 138, and the point between the condenser 138 and the resistance 164 is connected through a grid leak resistance 165 to ground and to one grounded terminal of the cathode 166 of the discharge device 160.

Even though the alternating signal voltage from the source 132 may be in the order of a few millivolts, the amplification in the discharge device 160 is enormous and the signal potential on the second anode 15 may be in the order of several volts. Such alternating potentials ap-

plied between the control electrode 163 and cathode 166 of the discharge device 160, where there is no negative bias potential provided, may cause the control electrode 163 to draw substantial amount of current from the electron stream in the discharge device 160. During normal operation of the device 160, the control electrode 163 does not draw such current, and the input of the device 160 is accordingly very high, and the device 160 can be very satisfactorily adjusted as previously explained for highly stable operation with very high gain. However, if the impedance between the control electrode 163 and the cathode 166 decreases abruptly, as during the short period when current flows in the control electrode 163, the impedance between the anode 15 of the device 160 and ground also changes abruptly, and in fact may be reduced sufficiently to cause bursts of self-sustained oscillation. Such bursts of oscillation, occurring during portions of each cycle of amplified voltage, are most undesirable. The addition of a condenser 167 in shunt with the resistance 135 to adjust the time constant of circuits associated with the first anode 13 is not effective to prevent such short bursts of oscillation during each cycle of the amplified signal wave.

The resistance 164 is made sufficiently large that, even when the control electrode 163 takes current when it is made positive with respect to the cathode 166, the impedance from the anode 15 through the coupling condenser 138 to ground is not reduced sufficiently to cause the device 160 to produce such bursts of self-sustained oscillation. It is evident that, in general, the larger the resistance 164, the closer can the adjustment of the device 160 approach that point at which self-induced oscillation would persist.

It should be noted that the condenser 167, connected in shunt with resistance 135 in Fig. 16, performs substantially the same function as the condenser 140, connected in shunt with the resistance 134 in Fig. 14.

In Fig. 17 the discharge device 170 is illustrated which is identical with the discharge device illustrated in Figs. 7 and 8, and for the sake of convenience, the electrodes are given like reference numerals. Since certain of the circuit elements associated with the discharge device 170 are similar to those illustrated in Fig. 13, they are also given like reference numerals to those in Fig. 13. The space charge electrode 70 is connected to the cathode 11 through a suitable source 171 of potential, so poled as to maintain the space charge electrode 70 at a suitable positive potential with respect to the cathode 11. The first control electrode 71, the first anode 72, the second control electrode 73, and the second anode 74 are connected in a manner analogous with the corresponding first control electrode 12, first anode 13, second control electrode 14 and second anode 15 of Fig. 13.

As pointed out previously in connection with the description of the discharge device itself, as illustrated in Figs. 7 and 8, the potential of the source 133 may be substantially smaller than is the case in Fig. 13 to achieve equal gain, or, alternatively, where the same source 133 is used, much higher gain can be achieved in the arrangement illustrated in Fig. 17, because the space charge electrode 70 provides substantial cathode current even when the anodes 72 and 74 are operated at what would otherwise be abnormally low potential.

The general adjustments of the circuit are sim-

ilar to those previously described, and, if desired, the condenser 172 may be connected in shunt with the resistance 135, so that the arrangement may be adjusted as explained in connection with Fig. 14. That is, as explained previously it is a matter of choice whether the condenser 172 or its equivalent is placed in parallel with resistance 134 or resistance 135. That is, condenser 167 connected in shunt with resistance 135 in Fig. 16 is of such magnitude that it produces the same desired result as is the case when a condenser 140 in Fig. 14 for producing the same effective time constant is connected in parallel to resistance 134. In other words, the time constant of the circuit connected between ground and anode 13 may be adjusted to have a predetermined time constant either by placing an impedance in parallel with resistance 134 or by placing an impedance in parallel with resistance 135. Alternatively, the condenser 172 may be omitted and the circuit adjusted as explained in Fig. 13.

In Fig. 18 there is illustrated a circuit arrangement utilizing the discharge device illustrated in detail in Figs. 10 and 11. It should be understood that this type of discharge device can of course be utilized in the circuit arrangement of Figs. 13 through 17. For the sake of convenience, the discharge device 180 in Fig. 18 has the same reference numerals applied to its electrodes as are applied to the electrodes illustrated in Fig. 10. A source 181 of alternating potential, having frequencies covering a substantial band, is connected between the control electrode 93 and the grounded cathode 91. The negative terminal of a source 182 of anode current is grounded, and the positive terminal of the source 182 is connected to the first anode 92 through a tuned circuit, including in parallel an inductance 183 and a condenser 184. A coupling condenser 185 is connected between the first anode 92 and the second control electrode 95, which in turn is connected through a resistance 186 to ground. The second anode 94 is connected to the positive terminal of the source 182 through a parallel tuned circuit including the primary inductance 187 of a transformer having a secondary 188, a condenser 189 and a resistance 190. The secondary 188 of the transformer is connected to a suitable load 191, which may, if desired, include a resistance component of such magnitude as to replace resistance 190, which can then be omitted.

The operation of the arrangement is similar to the operation of the previously described circuit arrangements. Signals to be amplified may, for example, be a carrier wave, modulated, for example, by audio or television signals or the like.

In order to avoid self induced oscillation, as explained previously, the inequalities previously described are preferably satisfied for efficient and high gain operation. In this case, R_1 , R_2 and G_m have the same meaning as in the case of previous circuits. Z_1 , for the illustrated circuit, represents the parallel impedance of condenser 184, inductance 183 and resistance 186, the reactance of coupling condenser 185 being negligibly small. Z_2 represents similarly the resistive, and reactive components of impedances between anode 94 and ground (not including internal anode resistance). Z_2 includes resistance 190, condenser 189, and the reactance and resistance appearing across the primary 187 of the transformer (due at least in part to load 191). To satisfy the inequality, in general, the L/C ratio of the two tuned circuits and the resistances associated with each may be

adjusted while maintaining the desired band width.

While we have shown and described the particular embodiments of this invention, it will be obvious to those skilled in the art that changes and modifications may be made without departing from this invention in its broader aspects, and we, therefore, aim in the appended claims to cover all such changes and modifications as fall within the true spirit and scope of this invention.

We claim:

1. The combination with an electron discharge device having a first control electrode, a first anode, a second control electrode and a second anode lying serially along a single electron discharge stream, said second control electrode and second anode being adjacent, of means for impressing alternating signal voltages on said first control electrode, means for impressing amplified signal voltage from said first anode upon said second control electrode, said last means comprising a resistance which forms at least a portion of the load circuit for said first anode, and means for producing amplified alternating voltages on said second anode, said last means comprising a complex impedance which forms at least a portion of the load circuit for said second anode and which at some frequency operates to increase the amplification of said device sufficiently to cause undesired self-oscillation, the time constants of said load circuit for said first anode and of said load circuit for said second anode being substantially equal so that said device cannot produce undesired self-oscillation.
2. In combination with an electron discharge device having a first control electrode, a first anode, a second control electrode and a second anode lying serially along the same electron discharge path, said second control electrode and said second anode lying adjacent each other, means for impressing alternating signal voltages on said first control electrode, means for impressing amplified signal voltages from said first anode upon said second control electrode, said last means comprising a complex impedance formed by a resistance and a condenser connected in shunt with each other and conductively connected with said first anode, and means for producing amplified signal voltages on said second anode, said last means comprising a complex impedance which at some frequency reacts with said device in the absence of said condenser to cause self-sustained oscillations, said resistance and condenser having such magnitude that their combined impedance changes with respect to changes of said complex impedance in such a manner as to prevent the production of self-sustained oscillation by said device.
3. In combination with an electron discharge device having a first control electrode, a first anode, a second control electrode and a second anode lying serially along the same electron discharge path, said second control electrode and said second anode lying adjacent each other, means for impressing alternating signal voltages on said first control electrode, means for impressing amplified signal voltages from said first anode upon said second control electrode, said last means comprising a complex impedance formed by a resistance and a condenser connected in shunt with each other, and means for producing amplified signal voltages on said second anode, said last means comprising a complex impedance which at some frequency reacts with said device in the absence of said condenser to cause self-

sustained oscillations, said resistance and condenser having such magnitude that their combined impedance changes with respect to changes of said complex impedance in such a manner as to prevent the production of self-sustained oscillations by said device.

4. In combination with an electron discharge device having a first control electrode, a first anode, a second control electrode and a second anode lying serially along the same electron discharge path, said second control electrode and said second anode lying adjacent each other, means for impressing alternating signal voltages on said first control electrode, means for impressing amplified signal voltages from said first anode upon said second control electrode, said last means comprising a complex impedance formed by a resistance and a condenser connected in shunt with each other, and means for producing amplified signal voltages on said second anode, said last means comprising a complex impedance which at some frequency reacts with said device in the absence of said condenser to cause self-sustained oscillations, the impedance of said resistance and condenser being substantially larger than said complex impedance and said resistance and condenser having such magnitude that their combined impedance changes with respect to changes of said complex impedance in such a manner as to prevent the production of self-sustained oscillations by said device.

5. In combination with an electron discharge device having a control electrode, a first anode, a second control electrode and a second anode all lying serially along a single electron discharge path, said second control electrode and second anode lying adjacent each other, means for impressing alternating signal voltages on said first control electrode, means for impressing amplified signal voltages from said first anode upon said second control electrode, said means comprising a complex impedance formed by a resistance and a condenser connected in shunt and conductively connected with said second control electrode, and means for producing amplified signal voltages on said second anode, said last means comprising a second complex impedance which in the absence of said condenser causes self-sustained oscillations in said device at some frequency, said resistance and condenser having such magnitudes as to prevent such production of self-sustained oscillations at any frequency within the desired range of frequencies.

6. In combination with an electron discharge device having a first control electrode, a first anode, a second control electrode and a second anode lying serially along a single electron discharge path, said second control electrode and second anode lying adjacent each other, means for impressing alternating signal voltages on said first control electrode, means for impressing amplified signal voltages from said first anode upon said second control electrode, said last means comprising a complex load impedance for said first anode having a resistance connected in shunt with a series arrangement of a condenser and a second resistance, and means for producing amplified signal potentials on said second anode, said last means comprising a complex impedance which, in the absence of said serial arrangement of condenser and resistance, tends to cause said device to produce self-sustained oscillations, said condenser and said two resistances having such magnitude as to suppress the production of such

oscillations at all frequencies within a desired band of frequencies.

7. In combination with an electron discharge device arranged for operation over a predetermined range of frequencies, said device having a first control electrode, a first anode, a second control electrode, means for impressing amplified signal voltage from said first anode upon said second control electrode whereby said device tends to oscillate at some frequency within or outside said range of frequencies, and a second anode lying serially along a single electron discharge path, a load impedance connected with each of said anodes, and means for making the time constant of said load impedances similar to prevent said device from producing self-sustained oscillations.

8. In combination with an electron discharge device having a first control electrode, a first anode, a second control electrode, and a second anode all lying serially along a single electron discharge path, a load impedance connected with each of said anodes, means for impressing amplified signal voltage from said first anode upon said second control electrode whereby said device tends to produce self-sustained oscillations at some frequency within a predetermined range of working frequencies, and means for making the time constants of said load impedances similar to prevent the production of such self-sustained oscillation.

9. In combination with an electron discharge device having a first control electrode, a first anode, a second control electrode, and a second anode all lying serially along a single electron discharge path, a load impedance connected with each of said anodes, means for impressing amplified signal voltage from said first anode upon said second control electrode whereby said device tends to produce self-sustained oscillations at some frequency within a predetermined range of working frequencies, means for making similar the time constants of said load impedances to prevent the production of such self-sustained oscillation, said load impedance connected with said second anode including an element whose impedance changes abruptly in large amount during instantaneous signal voltage peaks, and a fixed impedance connected serially with said element in said load impedance, said fixed impedance being sufficiently large that abrupt changes in impedance of said element do not substantially affect the time constant of said load impedance connected with said second anode.

10. In combination with an electron discharge device having a first control electrode, a first anode, a second control electrode, and a second anode all lying serially along a single electron discharge path, a load impedance connected with each of said anodes, means for impressing amplified signal voltages from said first anode upon said second control electrode whereby said device tends to produce self-sustained oscillations at some frequency within a predetermined range of working frequencies, means for making the time constants of said load impedances similar to suppress the production of such self-sustained oscillation, said load impedance connected with said second anode including an element whose impedance changes abruptly in large amount during instantaneous signal voltage peaks, and a resistance serially connected with said element and being of sufficient magnitude that abrupt impedance changes of said element do not sub-

stantially affect the time constant of said load impedance connected with said second anode.

11. In combination in an electron discharge device having a space charge electrode, a first control electrode, a first anode, a second control electrode and a second anode lying serially along a single electron discharge path, means for impressing amplified voltages from said first anode upon said second control electrode whereby said device tends to oscillate, and means for making the time constants of circuits connected with said anodes similar to suppress any tendency of said device to oscillate.

12. In combination, an electron discharge device having a first control electrode, a first anode, a second control electrode and a second anode lying serially along a single electron discharge path, means for impressing alternating voltages having high frequencies lying within a predetermined range of high frequencies upon said first control electrode, means for impressing amplified high frequency voltages in said predetermined range of frequencies from said first anode upon said second control electrode, said last means comprising a damped resonant circuit, and means for producing amplified high frequency voltages on said second anode said last mentioned means comprising a complex impedance of such magnitude as to suppress any tendency of said device toward self-sustained oscillations within said predetermined range of frequencies.

13. In combination, an electron discharge device having a first control electrode, a first anode, a second control electrode and a second anode lying serially along a single electron discharge path, means for impressing alternating voltages having high frequencies lying within a predetermined range of high frequencies upon said first control electrode, means for impressing amplified high frequency voltages in said predetermined range of frequencies from said first anode upon said second control electrode, said last means comprising a damped resonant circuit, and means for producing amplified high frequency voltages on said second anode, said last means comprising a second damped resonant circuit, the damping of said resonant circuits and the reactances thereof being of such magnitude as to suppress any tendency of said device toward self-sustained oscillations within said predetermined range of frequencies.

14. In combination, an electron discharge device having a first control electrode, a first anode, a second control electrode and a second anode lying serially along a single electron discharge path, means for impressing alternating voltages having high frequencies lying within a predetermined range of high frequencies upon said first control electrode, means for impressing amplified high frequency voltages in said predetermined range of frequencies from said first anode upon said second control electrode, said last means comprising a damped resonant circuit, and means for producing amplified high frequency voltages on said second anode, said last means comprising a second damped resonant circuit, the impedance of the resonant circuit connected with said first anode being so related to the impedance of said other resonant circuit at any frequency within said predetermined range of frequencies that any tendency of said device to produce self-sustained oscillations at such frequency is suppressed.

15. In combination, a discharge device having a first anode, a control electrode and a second anode all lying serially along a single electron discharge path, means for impressing amplified signal voltages from said first anode upon said second control electrode whereby said device tends to oscillate, and a load impedance connected with each of said anodes, said load impedances having similar time constants to prevent the production of self-sustained oscillations.

16. In combination, a discharge device having a first anode, a control electrode and a second anode lying serially along a single electron discharge path, means for impressing voltage from said first anode upon said control electrode whereby said device tends to oscillate, said means comprising a load impedance connected with said first anode, and a load impedance connected with said second anode, said load impedances having similar time constants to prevent the production of self-sustained oscillations.

17. In combination, a discharge device having a first anode, a control electrode and a second anode all lying serially along a single electron discharge path, a load impedance connected with each of said anodes, means for impressing amplified signal voltages from said first anode upon said second control electrode whereby said device tends to oscillate, and a load element forming a part of the load impedance connected with said second anode, said load element being subject to substantial changes of impedance under certain operating conditions and having a fixed impedance of substantial magnitude in series therewith, the magnitude of said fixed impedance being sufficient to prevent substantial changes in impedance of said load element from affecting the time constant of the load impedance connected with said second anode, said load impedances having similar time constants to prevent the production of self-sustained oscillations.

18. In combination, a discharge device having a first anode, a control electrode and a second anode all lying serially along a single electron discharge path, a load impedance connected with each of said anodes, means for impressing amplified signal voltage from said first anode upon said control electrode whereby said device tends to oscillate, and a load element forming a part of the load impedance connected with said second anode, said load element being subject to substantial changes of impedance under certain operating conditions and having a fixed resistance of substantial magnitude in series therewith, the magnitude of said fixed resistance being sufficient to prevent substantial changes in impedance of said load element from affecting the time constant of the load impedance connected with said second anode, said load impedances having similar time constants to prevent the production of self-sustained oscillations.

19. In an amplifier, the combination of an electron discharge device having five electrodes including a cathode, a first control electrode, a first anode, a second control electrode and a second anode lying serially along a single electron discharge path, means for impressing a signal potential between said first control electrode and cathode, means for producing amplified signal potential on said first anode and for impressing such amplified signal potential on said second control electrode, and means for developing amplified signal potential on said second anode, said second control electrode having a static voltage amplification factor sufficiently large that cur-

rent in said second anode remains substantially cut off with said second control electrode near that potential at which current begins to flow in said second control electrode as the continuous potential of a source to which said second anode is connected rises from zero voltage to a substantial positive voltage.

20. In an amplifier, the combination of an electron discharge device including a first control electrode, a first anode, a second control electrode and a second anode lying serially adjacent each other along a single electron discharge path, said device having separate connections to said anodes, means for impressing a signal potential on said first control electrode, means for producing amplified signal potential on said first anode and for impressing said amplified signal potential on said second control electrode, and means for developing amplified signal potential on said second anode, means maintaining said first and second anodes at substantially the same continuous potential, said second control electrode being so constructed that, with substantially equal potentials on said anodes and the potential of said second control electrode near that potential at which electron current begins to flow therein, substantial changes are effected in the electron current distribution between said anodes by small potential changes of said second control electrode.

21. In an amplifier, the combination of an electron discharge device including a first control electrode, a first anode, a second control electrode and a second anode lying serially adjacent each other along a single electron discharge path, said device having separate connections to said anodes, means for impressing a signal potential on said first control electrode, means for producing amplified signal potential on said first anode and for impressing said amplified signal potential on said second control electrode, and means for developing amplified signal potential on said second anode, said second control electrode being so constructed that, with substantially equal potentials on said anodes and the potential of said second control electrode near that potential at which electron current begins to flow therein, substantial changes are effected in the electron current distribution between said anodes by small potential changes of said second control electrode, said signal producing means and said signal developing means having substantially the same time constant throughout the range of frequencies of said signal potential.

22. In combination, an electron discharge device having a first control electrode, a first anode, a second control electrode and a second anode lying serially along a single electron discharge path, means for impressing a signal potential on said first control electrode, means for transferring amplified signal potential from said first anode to said second control electrode, said transferring means comprising a load impedance connected with said first anode, and means for developing amplified signal potential on said second anode, said developing means comprising a second load impedance, the ratio of said second load impedance to said first load impedance being as small as possible, allowing for the tolerance of elements available to form said load impedances, that said device does not produce self-sustained oscillations.

23. In combination, an electron discharge device having a first control electrode, a first anode,

a second control electrode and a second anode lying serially along a single electron discharge path, means for impressing a signal potential on said first control electrode, means for transferring amplified signal potential from said first anode to said second control electrode, said transferring means comprising a load impedance connected with said first anode, and means for developing amplified signal potential on said second anode, said developing means comprising a second load impedance, the ratio of said second load impedance to said first load impedance being at least as small as the static voltage amplification factor of said second control electrode with respect to said second anode but not so small as to produce self-sustained oscillation.

24. In combination, an electron discharge device having a first control electrode, a first anode, a second control electrode and a second anode lying serially along a single electron discharge path, means for impressing a signal potential on said first control electrode, means for transferring amplified signal potential from said first anode to said second control electrode, said transferring means comprising a load impedance connected with said first anode, and means for developing amplified signal potential on said second anode, said developing means comprising a second load impedance, said load impedances being so adjusted that, allowing for the tolerances of elements available to form said load impedances, the gain of said electron discharge device is as high as possible without the production of self-sustained oscillations, the ratio of said second load impedance to said first load impedance being at least as small as the static voltage amplification factor of said second control electrode with respect to said second anode.

25. In combination, an electron discharge device including a first control electrode, a first anode, a second control electrode and a second anode all lying serially adjacent along the same electron discharge path, a first impedance Z_1 connected with said first anode, a second impedance Z_2 connected with said second anode, means for impressing a signal potential on said first control electrode, and means for impressing amplified signal potential from said first anode upon said second control electrode whereby amplified signal potential appears on said second anode, said impedances being of such magnitude that at any frequency

$$\frac{(Z_1 + R_1)(R_2 + Z_2)}{Z_1 R_1}$$

is greater than $R_2 G_m$ in which inequality, R_1 is the internal resistance of said first anode, R_2 is the internal resistance of said second anode and G_m is the static transconductance from said second control electrode to said first anode.

26. In combination, an electron discharge device including a first control electrode, a first anode, a second control electrode and a second anode all lying serially adjacent along the same electron discharge path, a first impedance Z_1 connected with said first anode, a second impedance Z_2 connected with said second anode, means for impressing a signal potential on said first control electrode, and means for impressing amplified signal potential from said first anode upon said second control electrode whereby amplified signal potential appears on said second anode, said impedances being of such magnitude that at any frequency

29

$$\frac{(Z_1 + R_1)(R_2 + Z_2)}{Z_1 R_1}$$

is greater than $R_2 G_M$ in which inequality, R_1 is the internal resistance of said first anode, R_2 is the internal resistance of said second anode and G_M is the static transconductance from said second control electrode to said first anode, said device and said impedances being subject to variation as commercially available and said impedances being so chosen that, in a desired range of frequencies, said inequality has a minimum in or near said desired range.

27. In an amplifier, the combination of an electron discharge device including a first control electrode, a first anode, a second control electrode and a second anode lying serially adjacent each other along a single electron discharge path, said device having separate connections to said anodes, means for impressing a signal potential on the first control electrode, means for producing amplified signal potential on said first anode and for impressing said amplified signal potential upon said second control electrode, and means for developing amplified signal potential on said second anode, means maintaining said first and second anodes at substantially the same continuous potential, said second control electrode being so constructed that, with substantially equal potentials on said anodes and the potential of said second control electrode near

30

that potential at which electron current begins to flow in said second electrode, substantial changes are effected in the electron current distribution between said anodes by small potential changes of said second control electrode, said signal producing means and said signal developing means comprising separate load impedances so related in magnitude and character at all frequencies throughout the range of frequencies of signal potential as to prevent self-sustained oscillation of said amplifier.
